UNITED STATES PATENT OFFICE.

JOSEPH KUHNE, OF ISERLOHN, GERMANY.

APPARATUS FOR MAKING IN THE COLD SCREW BLANKS, RIVETS, AND SIMILAR HEADED ARTICLES.

Application filed January 28, 1924. Serial No. 689,201.

To all whom it may concern:

Be it known that I, JOSEPH KUHNE, manufacturer, a citizen of the German Republic, and residing at Iserlohn, Province of Westphalia, Germany, have invented certain new and useful Improvements in Apparatus for Making in the Cold Screw Blanks, Rivets, and Similar Headed Articles, for which I have filed applications in Germany on July 10 3, 1922, Ser. Nr. K. 82600 I/49g; August 19, 1922, Ser. Nr. K. 83046 I/49g; and December 18, 1922, Ser. Nr. K. 84325 I/49g, and of which the following is a specification.

15 The subject-matter of the invention is a modification of the apparatus for making in the cold screw-blanks, rivets and similar headed articles described and claimed in my co-pending application Serial Nr. 689,- 20 200, filed January 28, 1924.

25 One object of my present invention is to prevent the formation of the sharp edge or burr at the front face of the bolt head which, in the process according to the afore- 30 said application, may result from the mass of the stock flowing into the unavoidable intervening space between the preliminary pressure punch and the hollow plunger surrounding said punch and the stock-end to be upset. Another object is to dispense with the backward movement of said plunger with respect to the preliminary stamping punch which movement, in the apparatus described in my co-pending application, 35 must be effected by the pressure of the upset material when spread out in the head-forming matrix.

With these objects in view my invention 40 consists of a new arrangement and combination of parts constituting an apparatus for making screw-blanks, rivets and similar headed articles. Reference is made to the annexed drawing in which—

45 Figs. 1 to 4 are four sectional side elevations of the new apparatus. Herein—

Fig. 1 indicates the position of the parts at the beginning of the pressure stroke,

Figs. 2 and 3 indicate two intermediate 50 positions and

Fig. 4 shows the position at the end of the pressure stroke.

Fig. 5 is an axial, longitudinal section on a larger scale, of the matrix and the front end of the plunger surrounding the prelimi-

nary stamping punch in the end position of 55 the pressure appliance, and

Figs. 6 and 7 are side and front views, respectively, of a hexagon screw-head produced according to the present invention.

Referring now to the drawings: *a* is a 60 stationary die having a matrix *a*¹ of the size and shape of the head to be formed. This matrix is so sunk into the die *a* that the final stamping die must enter the matrix in order 65 completely to close the matrix. *b* indicates the head of the reciprocating press-slide *c*, and *f* a sleeve exchangeably mounted in the head. In this sleeve is guided a second sleeve *g* which is controlled by a spring *h* tending to press it outwardly, its outward 70 movement being arrested by the screw *d* which engages in a groove in the sleeve *g*. The latter, in contradistinction to the device shown in my co-pending application Ser. Nr. 689,200, does not constitute part of 75 the stamping die but serves to limit the thrust of a third sleeve or hollow plunger directly surrounding the pressure pin and serves simultaneously for laterally closing the matrix during the first portion of the 80 pressing operation. In the sleeve *g* is guided the hollow plunger *q* which together with the pressure pin *k* constitutes the final stamping die proper, and which is axially 85 slideable in the sleeve *g* within certain limits. The plunger *q* is controlled by a compression spring *r* which bears against its rear 90 flange *q*¹ and against a shoulder on the sleeve *g*, said spring tending to force the plunger *q* into the sleeve *g*. A screw *s* engaging in a groove in the plunger *q* limits this movement in such manner that in the 95 normal position the pressure face of the plunger *q* is flush with the front face of the sleeve *g*. The plunger *q* has a bore *i* of the diameter of the rod to be headed. In this bore is guided the pressure pin *k* which at its rear end bears against the larger thrust rod *m*, the large end *n* of the latter bearing against the adjustable key *o* of the slide 100 *c*. The thrust rod *m* has a shoulder *m*¹ which, after a certain displacement of said thrust rod *m* and pressure pin *k* in the plunger *q*, strikes against the rear end of the latter and then drives the plunger *q* positively.

The total length of the pressure pin *k* and that portion of the thrust rod *m* which

is in front of the shoulder m^1 is so related to the length of the plunger q that at the end of that movement of the preliminary stamping punch formed by pin k and rod m 5 which is independent of the plunger q , i. e. when the rod m by means of its shoulder m^1 , positively engages the plunger q , the front end of the pressure pin k will project a certain distance from the plunger q .

10 The operation of the described apparatus is as follows:

After the rod p to be headed has been fed through the die a the distance corresponding to the mass of material to be 15 shaped, the press-slide c is moved leftwardly against the matrix a , the punch q and the sleeve g being slipped over the rod portion extending from the die a . As soon as sleeve g abuts against the die a the matrix or die 20 space in the latter is closed laterally by this sleeve, while the plunger q will not yet have entered said die space, so that this space, being enclosed by die a , sleeve g and plunger q has a greater clear width than corresponds 25 with the finished height of the head to be upset (Fig. 2). By striking against the matrix a the sleeve g and with it the plunger q are restrained from further movement while the slide c and with it the rod m and 30 pressure pin k advance with simultaneous compression of the spring h . During that time, the rod-portion projecting from the plunger q is pressed by the pressure pin k 35 into the die space or matrix a^1 , the mass being spread out laterally all round in said space (Fig. 3). As soon as the mass is pressed into the matrix the thrust rod m by means of its shoulder m^1 , now located 40 at the rear end of the plunger q , drives the latter forward while simultaneously compressing the spring r . In that way the plunger q and pressure pin k , which both 45 now act in common as a final stamping die and enter the die a^1 as such, completely 50 spread and press out the mass in the matrix, that is, convert it to its final form. The slide c thereupon again moves rightwardly, the plunger q and sleeve g returning to their 55 initial positions by the action of springs r and h respectively (Fig. 1). Simultaneously means not shown in the drawing again advance the rod p and cut off the finished article, whereupon the described operation is repeated.

When pressing that portion of the rod p which is surrounded by the plunger q into the matrix a^1 the pressure pin k at its front end projects somewhat from the 60 plunger q (Figs. 3, 4 and 5) and it keeps this position with respect to the plunger q also when the final pressing occurs. In that way, as Figs. 6 and 7 particularly show, a small recess or deepening α is pressed into 65 the front face of the bolt head, the bottom

of which recess corresponds to the cross section of the pressure pin. The extension of the face of the work-piece associated with that action completely eliminates the sharp edge or burr which would have 70 formed at the end of the rod p adjacent to the pressure pin k when the mass of this rod-end is pressed into the matrix, such formation being due to the mass flowing into the unavoidable intervening space between the pressure pin k and the wall of the bore of the plunger q . The otherwise necessary extra work in removing the small annular burr from the front face of the bolt-head is thus dispensed with. 75

It is obvious that many changes in the apparatus described may be made without departing from the spirit of the invention. For example, it is not necessary that the pressure face of the plunger q in its withdrawn position should be flush with the front face of the sleeve g . On the contrary the device might be modified in such manner that the pressure face of the plunger q lies behind the front end of the sleeve g , whereby still greater room for lateral flow of the mass upset by the pressure pin k is provided between the bottom of the matrix a and the plunger q . In this case also an alternative is possible in which the plunger q at the final pressing does not enter the die a . 90

The new machine may also be modified in this way, namely, the rod to be headed, instead of being fed through the die a , may be conducted through an opening laterally of the latter. In this case the blank is cut off in a manner known per se before being worked up by the pressure devices. The blanks cut off are then introduced between die a and plunger q by means of a carrier of a form known per se, the plunger being advanced on to the blank, whereupon the pressing operations proceed in the manner already described. 105

The arrangement of the device so that the pressure pin k projects from the plunger surrounding the preliminary stamping punch and in that way forms a recess in the front face of the bolt head or the like is applicable also to the apparatus shown and described in my co-pending application Ser. Nr. 689,200. Moreover this arrangement may be utilized, in the case of the heading of screws and the like, to form simultaneously on the front of the head either a slit for the insertion of a screw driver or a multiple sided hole for the insertion of a key. In the first instance the pressure pin k has on its pressure face a projecting rib for forming the slit in the screw-head, while in the second instance the pressure pin k and the bore of the plunger q surrounding it have a polygonal cross section, the pressure pin k projecting from the plunger a 115 120 125 130

distance equivalent to the desired depth of the hole.

Claims:

1. In an apparatus for making in the cold screw-blanks, rivets and similar headed articles, in combination: a stationary die comprising a head-forming matrix, a press-slide, a hollow plunger for inclosing the end of the stock to be upset, said plunger being slidably mounted in said press-slide, a preliminary stamping punch for pressing said stock-end out of said plunger into said head-forming matrix, said punch being guided in the bore of said plunger and resting against said press-slide, resilient means for coupling said punch and said plunger in the direction of their forward movement, and a shoulder on said punch for positively coupling said punch and said plunger, said plunger, after being positively coupled to said punch forming together with the latter a final stamping die. 45
2. In an apparatus for making in the cold screw-blanks, rivets and similar headed articles, in combination: a press-slide, a sleeve guided therein, a hollow plunger for inclosing the end of the stock to be upset, said plunger being guided for limited longitudinal movement in said sleeve, a spring tending to hold said plunger in its innermost position with respect to said sleeve, a stationary die comprising a head-forming matrix and forming at the same time an abutment for arresting said sleeve, a preliminary stamping punch for pressing said stock-end 50
3. In an apparatus for making in the cold screw-blanks, rivets and similar headed articles, in combination: a stationary die comprising a head-forming matrix, a press-slide, a hollow plunger for inclosing the end of the stock to be upset, said plunger being slidably mounted in said press-slide, a preliminary stamping punch for pressing said stock-end out of said plunger into said head-forming matrix, said punch being guided in the bore of said plunger and resting against said press-slide, means for temporarily arresting said plunger, resilient means for coupling said punch and said plunger in the direction of their forward stroke, and a shoulder on said punch adapted to abut against the rear end of said plunger for positively coupling said punch and said plunger, the length of that portion of said punch which lies in front of said shoulder being somewhat greater than the length of said plunger, so that the front end of said punch projects from the plunger when the coupling between punch and plunger takes place, said plunger, after being coupled with the said punch forming together with the latter a final stamping die. 55 60 65 70 75

In testimony whereof I affix my signature.
JOSEPH KUHNE.
